UNITED STATES PATENT OFFICE.

JOHN B. GOLDSBOROUGH, OF BROOKLYN, NEW YORK.

UNDERPINNING.

Original application filed October 31, 1918, Serial No. 260,514. Divided and this application filed October 15, 1925. Serial No. 62,669.

This invention relates to a method of underpinning buildings, and particularly buildings having a continuous wall foundation.

5 In my copending application, Serial No. 260,514, filed October 31, 1918, there is disclosed and claimed a method of underpinning a building which consists generally of producing excavations in the earth beneath and 10 in alignment with the foundation of the building while leaving it supported above each excavation as it is produced by the natural arching action of the foundation, and forming in the excavations sections of 15 a new foundation consisting of piers and arches supported by and spanning the piers.

The present application, which is a division of my copending application referred 20 to above, relates to an embodiment of the invention for use when the foundation wall is in such poor condition that there is danger 25 of portions of it giving away under their own weight when the excavations are made. In order to prevent this a reinforcing envelope or a supplemental footing of foundation 30 material is applied to the wall, which is then supported by its inherent arching action reinforced by that of the envelope, while the excavations are being produced 35 and filled with the foundation material constituting the underpinning.

The particular nature of the invention to which this specification relates, as well as other objects and advantages thereof, will 40 appear most clearly from a description of the preferred embodiment shown in the accompanying drawings in which like reference characters designate like parts in the several views:

45 Fig. 1 is a side view of a foundation wall supported in the manner disclosed by this invention, and

Fig. 2 is a cross section of the wall and its underpinning taken along line 2-2 of 50 Fig. 1.

In the drawings, 1 represents the rubble masonry foundation wall of a building having a cellar 2 beneath the floor 3, it being assumed that the wall is in such poor condition that its own arching action cannot be entirely relied on for supporting it above the excavations for the underpinning. An envelope 4 of concrete is therefore placed around the face of the wall that is in the 55 poorest condition, and also under the bottom

of the wall. The envelope 4 serves to reinforce the wall and prevent it from falling apart when sections of the earth beneath the wall are excavated.

The underpinning of the building is accomplished in the manner disclosed in the above mentioned copending application which will be briefly described.

Spaced shafts 5 are sunk underneath and 60 in alignment with the wall and its envelope 65 4, during which operation the natural arching action of the reinforced wall 1 bearing on the remaining columns 6 of earth is sufficient to temporarily support the weight of 70 the building. The shafts 5 are filled with 75 foundation material to form piers up to the under side of envelope 4 to underpin the building whereby its weight is transferred to a greater depth. In order to sink shafts 80 5 underneath and in alignment with the 75 wall and its reinforcing envelope 4, further additional excavations must be made along one side of the wall in order to make the under side thereof at the positions of the proposed piers accessible, which excavations 85 are filled up when the underpinning has been completed.

While this specification and the accompanying drawings disclose a specific form 90 of construction, it is to be understood that such disclosure is only employed for the purposes of illustration, and that changes 95 may be freely made in the form and method of emplacement without departing from the spirit of the invention within the scope of 100 the appended claim.

I claim:

The method of underpinning a building having a foundation wall of poor conditions which consists in reinforcing the wall by 95 constructing around a portion thereof an envelope of foundation material, excavating sections of the earth beneath and in alignment with the reinforced wall while leaving it supported temporarily by its natural 100 arching action reinforced by the envelope and constructing in the excavations spaced piers which in connections with the portions of the envelope lying between the piers transfer the load of the building to a greater 105 depth.

In testimony whereof I affix my signature.

JOHN B. GOLDSBOROUGH.
